UNITED STATES PATENT OFFICE.

LOUIS E. BALTZLEY, OF GLEN RIDGE, NEW JERSEY.

SPEAKER UNIT.

Application filed May 20, 1926. Serial No. 110,316.

Special objects of the present invention are to provide an actuating unit for sound reproducers of the loud speaker type, which will reproduce faithfully without distortion, the low pitch, the high pitch and the intermediate tones throughout the scale of audibility; which will be sufficiently sensitive to reproduce the lesser or lighter as well as the heavier, more dominant sounds; which will operate direct and without the losses which occur when a system of linkage connections is employed; which will be powerful in action and capable of producing the desired sound volume and which, furthermore, will be of relatively simple construction, consisting of but comparatively few parts, readily assembled and adjusted and suited to manufacture on a large scale basis.

The foregoing and other desirable objects are attained in this invention by certain novel features of construction, combinations and relations of parts hereinafter fully described and broadly claimed.

The drawings accompanying and forming part of this specification illustrate certain practical embodiments and uses of the invention. As these illustrations are primarily for purposes of disclosure, it should be understood that the structure may be modified and its mode of use be altered in various ways without departure from the true spirit and scope of the invention as herein defined and claimed.

Figure 1 is a plan view of a speaker unit embodying features of the invention.

Figure 2 is a longitudinal sectional view of the same as on the line 2—2 of Figure 1.

Figure 3 is a cross sectional view of the unit as on substantially the plane of line 3—3 of Figure 2.

Figure 4 is a detached perspective view of one of the double pole pieces and Figure 4^a is a view of a modification.

Figure 5 is an enlarged sectional view of the resilient armature mounting, somewhat exaggerated to illustrate the action of the magnet thereon.

Figure 6 is a broken plan view of the armature and its resilient mounting strip.

Figure 7 is a cross sectional view illustrating the use of the unit with a cone type speaker.

Figure 8 is a part sectional view showing the adaptation of the invention to a speaker of the horn type.

Figures 9—10 are broken detail views of a modification in which the armature is attached only to the intermediate portion of the supporting strip and has only a simple to and fro movement with respect to the magnet. 80

Figures 11—12 are similar views illustrating a modification in which the magnet system is polarized to produce a rocking movement of the armature. 65

Figures 13 and 14 are side and end sectional views of a modified form of strip tensioning means.

Figure 15 is a cross sectional view illustrating embodiment of the invention in a 70 structure of the bi-polar magnet type.

The permanent portion of the magnet system is shown in the illustration as consisting of a single fairly heavy "horse shoe" or U-shape magnet 10. The flux of this magnet is concentrated and controlled to effect a four-way push-pull action on the armature in Figures 1 to 10 by providing special pole pieces 11, 12, having polar projections 11^a, 11^b and 12^a, 12^b respectively, arranged as indicated in Figure 5 so that like pole tips stand diagonally opposite on different sides of an intermediate plane and with unlike poles immediately opposite on different sides of the same plane. 75 80 85 90 95

This arrangement of polar tips is effected in the illustration by making each pole piece as indicated in Figure 4, with substantially parallel side portions 13, 14 connected integrally by an intermediate diagonal brace 15 and by arching one side downwardly as at 16 to carry one polar projection to a plane below the armature level and the other side upwardly as at 17 to carry the other polar tip to a position above the armature plane. 90

These pole pieces are shown arranged transversely at the ends of the U magnet, projecting inwardly toward each other and with their polar tips in opposition, being secured in this position with the lower edges 100 of the side portions resting on top of the magnet and held so by square washers 18 bearing on the upper edges of the side portions, said washers being secured by bolts 19 extending down through openings 20 in the diagonal braces and through the arms of the magnet into the supporting base 21.

These two bolts thus serve both to secure the magnet on the base and the pole pieces in fixed relation on the magnet. The magnet 110

and pole pieces are faced off so that the act of assembling these parts serves to automatically position them in proper relation.

The gaps between the pole tips of opposite polarity are alined to provide a narrow operating space for the armature, which is shown as a thin flat bar or strip 22 of suitable magnetic material. Directly connected with this armature is a power applying rod 10 or stylus 23 by which the vibrations are imparted to the sound wave creating member, which latter is shown at 24 in Figure 7 as of the cone type and at 25 in Figure 8 as of the diaphragm type acting in conjunction with 15 a horn 26.

A special feature of the present invention is the manner in which the armature is mounted in the magnetic field. This mounting is shown as a narrow thin strip or ribbon 20 27 of strong elastic material such as phosphor bronze stretched taut between two end supports or abutments and having the armature fixedly secured on the bridging portion thereof. The supports for this strip are illustrated as fret blocks 28, 29 secured by screws 30, 31 on the reversely inclined seats 32, 33 of the base, said screws passing also through the strip to anchor the same. Screws 34, 35 extending upwardly through the base, bear 30 on the inner or upwardly tilted end portions of the fret blocks and serve as a means for tilting these blocks to position the supporting strip and the armature carried thereby centrally in both of the magnetic gaps.

35 For tensioning the supporting strip an adjusting screw 36 is provided in Figures 1 and 2 acting on a cross bar 37 which presses a bight in the strip into a cross cavity 38 in the fret block 29.

40 A convenient and practical method of mounting the armature on the flexible supporting strip is illustrated in detail in Figures 5 and 6, where the strip is shown formed with a relatively wide slot 39 in the region 45 of the magnet poles and a communicating narrower slot 40 extending therefrom substantially to the adjacent fret block 28, the armature bar being shown as of a width to pass freely into the wider portion of the slot 50 and as being grooved in the sides thereof at 41 to slide into the narrower portion of the slot over the edges bounding the sides of the same. Once thus positioned the armature 55 may be secured in the desired relation by soldering or otherwise, as indicated at 42.

60 The actuating coil is shown as a single winding 43 carried by a hollow spool 44 and this spool is shown as positioned between the cheeks 16, 17 of the polar projections against properly located positioning lugs 45 on the inner faces of such cheeks. To fasten the coil 65 thus located, screws 46 may be utilized to draw the cheeks of each pair together and thus clamp the spool fixedly therebetween.

65 From Figure 2 it will be apparent that by

proper adjustment of anchorage screws 30, 31 and fret block adjusting screws 34, 35, the supporting strip may be raised or lowered at one or both ends to center the armature in both the magnetic gaps and that by means of screw 36 the tension of the supporting strip 70 may be increased or decreased to secure the desired or best action in the reproducer. This tension adjustment has the effect of controlling the tone or pitch of the speaker instrument. By increasing the stress the pitch 75 is raised and conversely by reducing the tension, the natural pitch is lowered. Similar and practically corresponding effects may be attained by increasing or decreasing the weight of the armature or by varying the length of the armature element. Thus, decreasing the weight or shortening the armature has the effect of raising the pitch while increasing the weight or lengthening the armature lowers the pitch. Because of these 80 possibilities the units may be manufactured or adjusted to suit different tonal qualities desired.

85 By reducing the tension, the unit may be made more susceptible to faint signals, but ordinarily the tension should be kept sufficient to prevent the armature from contacting the pole tips. Any tendency to contact the pole tips can be overcome by increasing the tension or by adjusting the fret screws to restore the armature to central position in the gaps.

90 The armature has the effect of making rigid that portion of the strip to which it is fixedly secured; namely, that part included by the bracket A in Figures 5 and 6.

95 The balance of the armature, that part included by bracket B, is free of the strip and so can move independently of the strip. This structural relation enables the supporting strip to hinge as on the line 47 substantially at the edge of the fret 28, the balance of the strip from the beginning of the wide slot at 105 48 to the other fret 29 being free to yield to the action of the magnet. This condition is exaggerated in Figure 5 where the free end 110 of the armature is illustrated as having swung about the fulcrum point 47 to a point where its free end is offset or out of line with the supporting strip. The movement of the free end of the armature being greater than that of the intermediate portion of the armature, the gap furthest removed from fulcrum 47 115 may be slightly wider than the nearer gap, as shown in Figure 5. These gaps should be small, consistent with the need of keeping the armature from contacting with the pole pieces and the ability to place any required tension on the supporting strip makes it 120 possible to keep the gaps at a minimum.

125 Figure 5 shows how the four way push-pull magnetic effect is obtained. The pole tips of similar polarity are diagonally opposite, with unlike poles immediately opposite so that 130

whichever way the armature is temporarily magnetized by the coil, there will be combined attraction and repulsion at both ends of the coil, all acting on the armature in the same direction so that a powerful effect is obtained in a slight range of movement. This is the effect desired for the operation of cone speakers and the like. The wide slot in the supporting strip increases the flexibility and 10 sensitivity of this support, enabling the armature to respond to relatively feeble signals, even when the strip is heavily tensioned.

The resilient mounting and supporting of the armature at both ends and the direct rigid 15 attachment of the stylus rod to this bodily movable armature make it possible to entirely support the cone or air vibrating member from the unit. For the purpose, a stiff stylus rod connection 23 may be employed. In 20 some cases it may be desirable to brace or guide the outer end of the stylus rod and to relieve it of any "whipping" tendency by extending it through a bearing such as shown at 49, in Figure 7, which may be in the form 25 of a sleeve lined with felt or the like.

In the modification illustrated in Figure 9, the armature is attached to the supporting strip at a point substantially midlength the coil and the movement is taken from this attached central portion. In this structure the 30 slot in the supporting strip is widened at both ends as at 39^a and the intermediate portion of the slot is restricted for a short distance as shown at 40^a. The restricted portion being 35 located approximately within the center of the coil, it follows that the armature will be held to the strip only at the center of the coil and will be free of the strip at both ends so that the strip can bow more or less without 40 twisting the armature and the armature therefore can have a straight bodily to and fro movement with respect to the magnet poles. The stylus rod is connected with this centrally attached portion and extends out through 45 an opening provided in the coil or between different sections of the coil. This construction has the advantage of imparting straight push and pull movements to the sound wave creating member.

50 The modification illustrated in Figure 10 is on the order of that just described, but in this instance the area of engagement between the armature and supporting strip is of less length, as shown at 40^b and the magnet system is polarized to effect a rocking movement 55 of the armature as indicated. The stylus rod in this case is connected with one end of the armature at a point just outside or inside one of the pole cheeks.

60 Various means for fixing the tension of the supporting strip may be employed, one simple practical device for this purpose being illustrated in Figure 9 and consisting of a sliding anchorage block 51 to which the supporting strip is attached and which has

forked rearwardly extending arms 52 sliding beneath overstanding shoulders in the abutment 53. A screw 54 extended through this abutment and engaging a screw seat in the sliding block serves to position said block 70 and hence enables the supporting strip to be set at any desired tension.

The extent to which the armature supporting strip is tensioned determines largely the pitch or tonal characteristics of the speaker 75 and this adjustment, therefore, may conveniently be used as a means for tuning the speaker to individual taste. The stress placed on the strip may amount to one hundred pounds or more. This is amply sufficient to hold the 80 armature centrally supported in a relatively narrow magnetic gap and to overcome the possibility of the armature contacting the polar projections. This construction eliminates the need for any centralizing springs or 85 other accessories and leaves the armature free to respond entirely to the magnetic forces set up by the coil. The supporting strip is so light, thin and flexible as to offer practically no opposition in the way of inertia, and the 90 armature, therefore is practically "floated" in a highly sensitive or responsive condition in the field of the magnetic system.

The various parts of the device are of simple structure and such as can readily be 95 standardized in production. These parts are such as can be manufactured accurately and then be quickly assembled in proper relation. The base contributes largely to the ease and accuracy of assemblage, being shown as provided with flat seats 55 at the sides of the same for the arms of the U magnet and with bridges or arched portions 56, 57 at the opposite ends formed to provide the raised inclined seats 32, 33 for the fret blocks. Between these raised seats the base is hollowed 100 at 58 to afford ample clearance for the polar projections and the coils supported therebetween. That part of the base which carries the seat for the outer anchorage block is shown as extending clear of the magnet structure and as perforated at 59 for screws or like fastenings 60, Figure 7, by which the unit may be secured on a suitable backing or support 61. In this latter view, the guide for 105 the outer end of the stylus rod is illustrated as carried by an arm 62 having a bent end secured beneath the anchorage screw 30 for the outer end of the supporting strip.

The invention is well adaptable to receivers of the bi-polar type such as shown in Figure 15, where 63 indicates an ordinary C magnet having polar projections 64 carrying coils 65. The flexible supporting strip is tensioned between the end supports 66, 67 and carries the armature strip positioned above the magnet poles. The stylus rod is shown directly connected with the armature strip as before described and may be used as above to actuate a diaphragm, cone or other sound wave gen- 115 120 125 130

erating device. Instead of using the ordinary cup shaped base such as common in these receivers, the base may be in the form of a spring yoke having projections to enter 5 openings in the ends of the supporting strip so as to impart the desired longitudinal tension to said strip.

Where, as for instance in Figures 1, 5 and 10, the relatively rigid armature strip is of greater length than the polar structure of the magnets, that section which extends beyond the polar structure may be of non-ferrous metal. Thus in the views referred to, the projecting portion 68 of the armature 15 strip may be a section of any suitable non-magnetic metal welded or otherwise rigidly secured to the magnetic portion of the armature strip by an end weld or other rigid joint 69 at a point outside or near the adjacent 20 pole pieces. This concentrates the magnetic action to those sections of the armature strip which are in the immediate range of the pole tips and prevents stray or waste of the magnetic energy. The armature proper, therefore, 25 may be made just the right length to be most efficient and the desired action be obtained by using with this armature, a non-ferrous extension strip of the length required to give such action.

30 In the rocking form of armature shown in Figures 11 and 12, it should be noted that the stylus rod 23, instead of being located outside the pole pieces may be located in a space provided therefor inside the adjoining pole 35 piece substantially as indicated in dotted lines in Figure 11.

The sound wave generating member usually is so light as to have little or no biasing effect on the armature. When the receiver 40 is positioned vertically as in Figure 7, any sagging tendency due to the weight of the cone may be offset by the guide for the stylus rod or by adjusting the supporting strip at one or both ends sufficiently to compensate 45 for the added weight and bring the armature to a normal centrally supported position in the gap when carrying the weight of the cone. When the device is arranged horizontally as in Figure 2, both ends of the strip 50 may be adjusted alike, for instance, to slightly raise the strip bodily. The cone may be applied to the stylus rod with the apex inward, instead of as shown in Figure 7, such arrangement permitting the use of a shorter 55 stylus rod.

As in the manufacture of the unit on a production scale, it is practically impossible to assemble the devices with the pole tips spaced exactly the right distance apart, 60 means may be provided for quickly effecting this result after the parts have been put together. Such means are shown in Figures 1, 2 and 4 as small taper screws 70 of brass or other non-magnetic material engaged with the companion screw seats 71 formed as ex-

tensions on the edges of opposing pole tips and thereby adapted to act as fine wedges for forcing the pole tips apart. In practice, the pole pieces are set up with the pole tips too close together and the separating screws 70 are then entered in the split screw seats until the pole tips are separated to the desired extent, which can be easily determined by entering a thickness gage between the tips. The two screws enable each gap to be independently set the proper width and the adjustments once made will be retained because of the binding action of the screws in the split screw seats.

In the structure shown in Figure 4^a, separating screws 70^a are employed, each mounted in a screw seat 71^a on the edge of one pole tip and bearing upon an extension lug 72 on the edge of the opposing pole tip. The action of these screws is the same as described 80 with respect to the wedging screws. This arrangement has the advantage that the screws can be reached from a position over the top of the unit.

In forms of the device such as illustrated 90 in Figure 5, it has been found desirable to extend the magnet strip, whether it be of the full magnetic or part magnetic construction close to the fret 28 so as to locate the hinge 47 at a fixed point, substantially at the edge 95 of the fret. That portion of the armature strip which extends from this fulcrum point and is rigidly secured to the supporting strip is in the nature of a lever. It will be apparent that by varying the length of this 100 lever section, that is, the portion included within bracket A, different effects may be obtained. For example, a heavier diaphragm or sound wave creating member requires increased longitudinal tension on the supporting strip. This increased tension has a tendency 105 to bind the armature or to carry its natural period too high. This tendency is overcome by simply decreasing the rigidly held portion of the armature, that is, the length 110 within bracket A until the proper balance is restored.

What is claimed is:

1. In combination, a base, a **U** magnet mounted on said base, a support on the base 115 between the arms of the **U** magnet, a support on the base beyond the ends of the magnet, a strip secured in bridging relation between said supports, an armature element carried by said strip and polar projections at the terminals of the magnet and positioned to operate on the armature element.

2. In combination, a base, a **U** magnet mounted on said base, a support on the base 125 between the arms of the **U** magnet, a support on the base beyond the ends of the magnet, a strip secured in bridging relation between said supports, an armature element carried by said strip, polar projections at the terminals of the magnet and positioned to operate 130

on the armature element and an energizing coil carried by said polar projections and surrounding the armature element.

3. In combination, a base, a **U** magnet mounted on said base, a support on the base between the arms of the **U** magnet, a support on the base beyond the ends of the magnet, a strip secured in bridging relation between said supports, an armature element carried by said strip, polar projections at the terminals of the magnet and positioned to operate on the armature element and an impulse transmitting connection projecting from said armature element.

4. In combination, a base, a **U** magnet mounted on said base, a support on the base between the arms of the **U** magnet, a support on the base beyond the ends of the magnet, a strip secured in bridging relation between said supports, an armature element carried by said strip, polar projections at the terminals of the magnet and positioned to operate on the armature element and means at one of the supports for variably tensioning the armature supporting strip.

5. In combination, a base, a **U** magnet mounted on said base, a support on the base between the arms of the **U** magnet, a support on the base beyond the ends of the magnet, a strip secured in bridging relation between said supports, an armature element carried by said strip, polar projections at the terminals of the magnet and positioned to operate on the armature element, said supports for the armature supporting strip comprising fret blocks and means for variably securing the same on the base.

6. In combination, a permanent **U** magnet having opposed polar projections at the extremities of the same, providing a magnetic gap therebetween, an armature disposed in the gap between said polar projections, a tensioned resilient supporting strip for said armature extending longitudinally between the sides of the **U** magnet, supports for said strip at opposite sides of the gap and means in conjunction with one of said supports for applying a stretching tension to that portion of the supporting strip extending through the magnetic gap.

7. In combination, a base having seats at opposite sides of the same and raised portions at opposite ends of the same, a **U** magnet supported on said side seats, a flexible strip tensioned between the raised portions of the base, an armature carried by said strip and polar projections at the ends of the magnet actively related to the armature.

8. In combination, reversely inclined frets, a resilient strip supported in tensioned relation on said frets, an armature element carried by said strip, a magnet system operatively associated with said armature and means for independently varying the inclination of said reversely inclined frets for the

purpose of variably positioning the opposite ends of said resilient armature supporting strip.

9. In combination, a permanent **U** magnet, pole pieces each comprising substantially parallel side portions connected by a diagonal brace, means for securing said pole pieces with the edges of the side portions bearing on the arms of the permanent magnet, the side portions of said pole pieces terminating in opposed polar tips and an armature positioned between the opposed polar tips.

10. In combination, a permanent **U** magnet, pole pieces each comprising substantially parallel side portions connected by a diagonal brace, means for securing said pole pieces with the edges of the side portions bearing on the arms of the permanent magnet, the side portions of each pole piece having reversely arched extensions terminating in pole tips disposed at opposite sides of a common intermediate plane and an armature interposed between said pole tips in said intermediate plane.

11. In combination, a permanent magnet having pole pieces, each of said pole pieces having unitary spaced parallel side portions connected by intermediate integral braces with oppositely faced polar tips disposed at opposite sides of an intermediate plane and an armature supported in said intermediate plane.

12. In combination, a permanent magnet having opposed pole pieces, each of said pole pieces having unitary laterally spaced substantially parallel side portions connected by intermediate integral braces and terminating in oppositely faced polar tips of like polarity disposed at opposite sides of an intermediate plane and an armature supported to operate between said pole tips.

13. In combination, a permanent magnet having opposed pole pieces, each of said pole pieces having unitary laterally spaced substantially parallel side portions connected by intermediate integral braces and terminating in oppositely faced polar tips of like polarity disposed at opposite sides of an intermediate plane and an armature supported to operate between said pole tips, the polar tips being connected with the main bodies of the side portions by deeply arched sections extending away from the intermediate plane.

14. In combination, a flexible strip, supports for the opposite ends of said strip, an armature extending longitudinally of said strip and rigidly attached to said strip for a portion of its length and free of the strip for the balance of its length and a magnet structure acting on said armature.

15. In combination, a flexible strip, supports for the opposite ends of said strip, an armature extending longitudinally of said strip and rigidly attached to said strip for a portion of its length and free of the strip for

the balance of its length and a magnet structure acting on said armature, said magnet structure including polar projections and a magnetizing coil positioned to operate on the free portion of the armature.

16. In combination, an armature supporting strip having a slot therein, an armature having a portion rigidly secured in one part of said slot and another portion free to operate in another part of said slot, supporting means for said strip and a magnet structure acting on said armature.

17. In combination, an armature supporting strip having a slot therein, an armature having a portion rigidly secured in one part of said slot and another portion free to operate in another part of said slot, supporting means for said strip and a magnet structure acting on said armature, said magnet structure including polar projections and a magnetizing coil positioned to act upon the free portion of said armature.

18. In combination, an armature supporting strip having a slot with a portion of reduced width, an armature element grooved in its opposite edges to fit over the edges bounding the reduced portion of the slot, an impulse transmitting connection associated with said armature and a magnet structure positioned to act on the armature.

19. In combination, spaced supports, a longitudinally tensioned resilient strip bridged between said supports, an armature element fixed on said strip closely adjacent to one of the supports and extending toward the other support and a magnet structure positioned to act on that portion of the armature projecting away from the support.

20. In combination, an armature supporting strip having a slot therein reduced in width at a point intermediate the ends thereof, an armature element engaged with the edge portions bounding the reduced section of the slot and free of the edges bounding the wider end portions of the slot and a magnet structure operating on said armature.

21. In combination, an armature supporting strip having a slot therein reduced in width at a point intermediate the ends thereof, an armature element engaged with the edge portions bounding the reduced section of the slot and free of the edges bounding the wider end portions of the slot and a magnet structure operating on said armature and including pole pieces polarized to effect movement of the armature in the same direction at both ends thereof.

22. In combination, an armature supporting strip having a slot therein reduced in width at a point intermediate the ends thereof, an armature element engaged with the edge portions bounding the reduced section of the slot and free of the edges bounding the wider end portions of the slot and a magnet structure operating on said armature and in-

cluding pole pieces polarized to effect reverse movements of the opposite ends of the armature, the attached portion of the armature being disposed intermediate the ends of the same to enable rocking movements of the same.

23. In combination, a sound wave creating member operating in free air, a relatively stationary telephone unit for actuating the same, said unit having a projecting stylus rod connected with the sound wave creating member and a guide for said stylus rod at the back of said member, said rod having a freely sliding engagement in said guide so as to be supported in and have its movements directed by said guide.

24. In combination, a telephone unit having a projecting stylus rod, a rigid relatively stationary guide for said rod and with which said rod has a free sliding engagement and a sound wave generating member supported on the portion of the stylus rod projecting beyond the guide.

25. In combination, a telephone unit having a projecting stylus rod, a rigid guide for said rod and a sound wave generating member supported on the portion of the stylus rod projecting beyond the guide, said guide including a rigid sleeve having a lining of felt-like material.

26. In combination, a tensioned supporting strip, a relatively rigid armature strip carried thereby and comprising magnetic and non-magnetic portions, arranged with the magnetic portion projecting away from the non-magnetic portion and a magnet system positioned to act only on the magnetic portion of said armature strip.

27. In combination, a magnet system, an armature element consisting of a magnetic portion located within the immediate range of action of the magnet system and a non-magnetic portion projecting beyond the immediate field of the magnet system and a flexible support connected with non-magnetic portion of said armature element.

28. In combination, an armature supporting strip, an anchorage for one end of the same, a slidably supported block to which the opposite end of said strip is secured, screw means for shifting said block to tension the strip, an armature element carried by the portion of the strip intermediate the end supports and a magnet structure positioned to act on said armature element.

29. In combination, an armature supporting strip, an anchorage for one end of the same, a slidably supported block to which the opposite end of said strip is secured, screw means for shifting said block to tension the strip, an armature element carried by the portion of the strip intermediate the end supports, a magnet structure positioned to act on said armature element and a post for guiding the sliding member, said post

and sliding member having slidingly related parts and the screw means being mounted in said post.

30. In apparatus of the character disclosed, 5 a longitudinally tensioned resilient supporting strip, an armature element carried by said strip, a magnet structure having pole pieces to act on said armature element, means for variably positioning the opposite ends of 10 said strip and means for varying the tensile stress on said armature strip.

31. As an article of manufacture, a pole piece for a permanent magnet comprising substantially parallel side members connected 15 in spaced relation by an intermediate brace extending diagonally from the edge of one member to the far edge of the other member, said members projecting longitudinally beyond said brace in oppositely arched extensions terminating in oppositely facing 20 polar tips.

32. The combination with a magnet, of a pole piece therefor having substantially parallel spaced sides connected by a diagonal brace, said sides extending beyond said brace and terminating in pole tips and means for securing said pole piece to the body of the 25 magnet.

33. The combination with a magnet, of a pole piece therefor having substantially parallel spaced sides connected by a diagonal brace, said sides extending beyond said brace and terminating in pole tips and means for securing said pole piece to the body of the 30 magnet, the polar extensions having reversely arched portions carrying the pole tips and said pole tips being faced in opposite directions.

34. In combination, a magnet structure including opposing pole tips of magnetic material separated by a narrow magnetic gap, an armature disposed in said gap, a magnet winding about the gap and armature and non-magnetic means adjustable for forcing 40 said pole tips apart to vary the width of the gap in which the armature is located, said adjustable means serving also to hold said pole tips separated in the position of adjustment.

35. In combination with a magnet system and an armature therefor, a resilient supporting strip for said armature and spaced supports for said strip, one of said supports being inclined away from the other support 50 and forming a fret over which the strip is bent.

36. In combination with a magnet system and an armature therefor, a resilient supporting strip for said armature and spaced supports for said strip, one of said supports being inclined away from the other support 60 and forming a fret over which the strip is bent and means for varying the inclination of said fret to variably position the armature strip accordingly.

37. In combination with a magnet system and an armature therefor, a resilient supporting strip for said armature and spaced supports for said strip, one of said supports being inclined away from the other support 70 and forming a fret over which the strip is bent, means for varying the inclination of said fret to variably position the armature strip accordingly and means for variably tensioning the armature strip independently of its support on said fret.

38. In combination, a flexible strip, an armature attached to said strip for a portion of its length and free of the strip for another portion of its length, a magnet structure having 80 polar projections positioned to operate on the free portion of said armature and means for variably tensioning said strip to control the action of the magnet on the free portion of the armature.

39. In combination, a flexible strip, an armature attached to said strip for a portion of its length and free of the strip for another portion of its length, a magnet structure having 90 polar projections positioned to operate on the free portion of said armature, means for variably tensioning said strip to control the action of the magnet on the free portion of the armature and an impulse transmitting member connected with the attached portion 95 of the armature.

40. In apparatus of the character disclosed, a longitudinally tensioned resilient supporting strip, an armature element carried by said strip, a magnet structure having pole pieces to act on said armature element, means for variably positioning said strip with respect to the pole pieces and means for varying the tensile tension on said armature strip independently of the positioning aforesaid.

41. In apparatus of the character disclosed, the combination with a magnet system and an armature actuated thereby, of a tensile tensioned resilient support for said armature, a free edge sound wave creating member carried by said resilient support and means for variably tensioning said support to position said sound member and to place the armature in proper operative relation to the magnet system.

42. In combination, a tensile tensioned resilient strip of non-magnetic material, a strip of magnetic material fixed to said non-magnetic strip, an impulse transmitting connection extending from said magnetic strip, a magnet structure having polar tips positioned to act on said magnetic strip, means for variably positioning the non-magnetic strip to thereby relate the magnetic strip to the pole tips and means operable independently of the positioning means for varying the tensile stress on the non-magnetic strip.

43. In combination, spaced end supports, a resilient strip supported in tensile tensioned condition by said end supports, an armature

element carried by said tensioned strip, an impulse transmitting connection extending from said armature element, a magnet system having two sets of opposed polar projections forming two magnetic gaps in which the armature element is located, said end supports being each adjustable to independently position the opposite ends of the armature element in the respective magnetic gaps and 10 means for independently varying the tensile stress of said supporting strip.

44. In apparatus of the character disclosed, a permanent magnet having opposed pole pieces closely spaced to form a thin but 15 relatively wide magnetic gap, a thin flat resilient strip of appreciable width extending through said magnetic gap, frets at opposite sides of the magnetic gap having supporting edges disposed toward the gap and on which 20 the supporting strip rests, a thin flat armature element rigidly affixed to said supporting strip and located in the magnetic gap aforesaid, a magnet winding surrounding said armature element and the strip carrying the 25 same, an impulse transmitting rod connected with said armature element and means for tensile tensioning and for bodily shifting the strip for centering the armature element in the magnetic gap.

45. In apparatus of the character disclosed, a permanent magnet of the horse-shoe type, a support between the arms of said magnet, a support located beyond the arms of the magnet, an armature strip secured in bridging relation between said supports, polar projections at the ends of the magnet arms positioned at opposite sides of the armature strip, means for variably tensile tensioning said armature strip, an electromagnetic winding 40 associated with the polar projections and an impulse transmitting connection extending from the armature strip at a point beyond the arms of the magnet.

46. In apparatus of the character disclosed, 45 a permanent magnet of the horse-shoe type, a support between the arms of said magnet, a support located beyond the arms of the magnet, an armature strip secured in bridging relation between said supports, polar projections at the ends of the magnet arms positioned at opposite sides of the armature strip, means for variably tensile tensioning said armature strip, an electromagnetic winding 50 associated with the polar projections, an impulse transmitting connection extending from the armature strip at a point beyond the arms of the magnet and means for effecting relative adjustment between the

armature strip and polar projections to locate the armature strip in the magnetic gap independently of the tensioning adjustment. 60

47. In apparatus of the character disclosed, a flat supporting strip of non-magnetic spring metal, a flat rigid armature strip of magnetic material secured thereto, a vibration transmitting element connected with said armature strip, a magnet structure having polar projections acting on said armature strip and a magnetizing coil positioned to act on said armature strip, said 70 armature strip being rigidly secured to the non-magnetic supporting strip for a portion of its length and free of the supporting strip for another portion of its length and arranged with said free portion subjected to the influence of the magnetizing coil. 75

48. In apparatus of the character disclosed, a flexible supporting strip, a relatively rigid armature strip rigidly secured to said supporting strip for a portion of its length 80 and free of the supporting strip for another portion of its length and a magnet structure including polar projections and a magnetizing coil, said coil and polar projections being positioned to act on the free portion of said 85 armature strip.

49. In apparatus of the character disclosed, a magnet system, an armature element consisting of a magnetic portion located within the immediate range of action 90 of the magnet system and a non-magnetic portion projecting beyond the immediate field of the magnet system, a flexible support connected with the non-magnetic portion and free of the magnetic portion of the armature 95 element and a vibration transmitting member connected with said armature element.

50. In apparatus of the character disclosed, a magnet provided with pole pieces defining a magnetic gap, an armature supported in said magnetic gap, a magnetizing coil for said armature, a rod projecting a distance from said armature, a guide engaged with the distant end portion of said rod at a point remote from the armature, said guide 100 being supported independently of the armature so as to be unaffected by vibrations of the armature and capable of guiding and sustaining the free end of the rod with the load of a sound wave generating element thereon 105 and a sound wave generating member carried by the rod and having its weight borne by the independently supported guide. 110

In witness whereof, I have hereunto set my hand this 17th day of May, 1926.

LOUIS E. BALTZLEY.
